COFFEE POT

Edward R. Swann, North Canton, Ohio, assignor to The Hoover Company, North Canton, Ohio, a corporation of Ohio

Application December 19, 1955, Serial No. 39,381

Term of patent 14 years

(Cl. D44—26)

I claim:

The ornamental design for a coffee pot, substantially as shown.
